COLLAPSIBLE OR KNOCKDOWN HORSE

Harold J. Marlowe, Brooklyn, N. Y., assignor, by
mesne assignments, to Marlowe Devices, Inc.,
New York, N. Y., a corporation of Delaware

Application November 20, 1931, Serial No. 576,243

9 Claims. (Cl. 304—5)

My present invention while applicable in its broader aspects to various types of collapsible or knockdown support frame structures, is primarily intended for embodiment in a horse for supporting scaffolding, or a carpenter's horse, saw-horse or the like.

An object of the invention is to provide a device of this character which will be exceptionally rigid and strong when in set up or extended position and will occupy a minimum space when collapsed for purposes of storage and transport.

Another object is to provide a horse constructed of but a few simple parts capable of being conveniently set up or knocked down at will and substantially proof against inadvertent disassembly or collapse during use.

Another object is to provide a device of this character of simple, rugged, durable construction well suited to meet the diverse requirements of its various and sundry usages and to withstand rough and careless handling to which such devices are frequently subjected.

Another object is to provide a structure of this class requiring no tools to set it up or knock it down and capable of being expeditiously erected or disassembled by any unskilled workman and a device which after once being set up may be conveniently transported from place to place within a room or about the site of an operation without danger of the parts loosening up or becoming displaced or disassembled.

In accordance with a preferred embodiment of the invention, the horse includes pairs of legs at its ends connected by a common cross member. Preferably all of the legs are identical and of angular conformation. The two legs of a pair are pivotally connected near their upper ends and at the elbow or bend which connects the angular offset portions of the legs with each other in such a manner that both ends of a leg are disposed at the same side of the pivot.

The upper ends of the legs are suitably shaped to cradle and support a cross member.

Due to the disposition of the pivot near the tops of the legs and the fact that the lower ends of the legs are normally spread further apart than the upper ends thereof, a load applied upon the cradled cross member will take effect as a force tending to clamp the two sides of the cradle together so that the greater the load imposed upon the horse, the more firmly will the load be clamped.

In accordance with one embodiment of the invention, the constituent elements consisting of the four identical legs and the cross pieces which

connect them, may be disassembled, laid one upon the other and held together only by the securing bolts which are employed in the erected structure in such a manner that they form a small compact knocked down unit which may be conveniently transported.

If desired, the horse may be provided with a unitary folding part adapted to receive a guard rail for coaction with the scaffolding planks, one end of which rest upon the horse.

When the invention is applied to a carpenter's horse, the cross piece, which is supported by the legs, is adapted to serve as a narrow bench upon which the carpenter may work, and downward pressure may be artificially applied to the bench as an incident of assembling the structure, whereby the bench is firmly clamped in its cradle.

The invention may be more fully understood from the following description in connection with the accompanying drawings, wherein:

Fig. 1 is a perspective view of a scaffolding supporting horse embodying the invention, showing the horse in set up condition and with a scaffolding and guard rail supported thereby,

Fig. 2 is a side elevational view showing the constituent parts of the horse knocked down and packed for purposes of shipment or storage,

Fig. 3 is a perspective view of the top cross bar of the horse and its associated guard rail supporting element in folded position,

Fig. 4 is a perspective view of one of the legs of the horse,

Fig. 5 is a view similar to Fig. 1, but illustrating the slightly modified form of construction employed when the invention is embodied in a carpenter's horse, and

Fig. 6 is an enlarged sectional detail on the line 6—6 of Fig. 5.

Referring first to Figs. 1 to 4 of the drawings, I have used the reference character L to designate the legs of the horse, there being a pair of legs at each end of the horse connected by a common cross member and pivot bar 10.

Each leg includes an elongated lower portion 11 integrally connected with a shorter upper portion 12 which is angularly offset from but in the same plane as section 11. These legs are preferably formed of steel bar stock. At or adjacent the point of junction at the two angularly offset portions of the legs, each leg is provided with an opening 13 for the reception of the cross bar 10. Immediately above the opening 13 each leg is apertured at 14, for a purpose which will more fully hereinafter appear, and each leg near its

lower end is provided with an aperture 15, the purposes of which will also be later described.

The upper shorter ends 12 of the legs are notched or recessed, as at 16, to define a substantially horizontal shoulder 17 which, when the legs are set up, constitutes half of a cradle within which is received a transverse top member 18 also of steel bar stock and engaged edgewise in the cradles afforded by the cooperating pairs of recesses 16 in the two pairs of legs.

10 The connecting cross pivot bar 10 may be of ordinary steel rod stock including reduced threaded ends 19, which pass through the apertures 13 in the legs L and receive wing nuts 20 pressing against washers 21 which work against the outer surface of the outermost leg of each pair.

With the construction as thus far described, it will be apparent that since the lower ends 11 of each pair of legs are spaced further apart than the upper ends 12 of such legs, pressure exerted downwardly on the cross member 18 will take effect as a spreading force on the leg portions 11 and consequently will tend to draw the leg portions 12 together contracting the cradle and more tightly gripping the cross bar 18. In other words, the greater the load applied upon the bar 18, the more firmly will this bar be gripped.

When the legs are set up, the apertures 14 in each pair of legs register with each other and eye bolts 22 may be passed through these aligned apertures and held in position by thumb nuts 23. These eye bolts are not vital to the proper support of the horse when the latter is set up, but as will more fully hereinafter appear, serve an important function in holding the constituent elements of the horse together when the latter has been knocked down and packaged.

In order to support a guard rail such, as for instance, as an ordinary 2" x 4" indicated at 24, which will prevent workmen from tumbling off the scaffolding planking 25, which is supported on the cross bar 18, I may utilize a pivoted arm 26 also of steel bar stock. One end of this arm is connected to one end of the bar 18 by a pivot pin 27 and the arm is notched as at 28 so that it may be folded as shown in Fig. 3 without interfering with a laterally projecting pin 29 fixed to the cross bar 18. One purpose of this pin 29 is to serve as abutment or gauge when placing the bar 18 in the legs of the horse and the other purpose of the pin is to limit the pivotal movement of the guard rail support bar 26. Bar 26 near its top has a notch or recess 30 in its edge adapted to receive the rail 24, and a removable pin 30" working through the end of the bar 26 may be dropped in place to lock the guard rail against lateral displacement from the notch.

The rail 18 is provided with a pair of openings 31 and 32 therein spaced apart a distance equal to the spacing between the openings 14 and 15 of the legs. Due to the friction between the pivot pin 27 and the rail supporting arm 26, the arm 26 will not swing inwardly under the weight of the guard rail. The only substantial force tending to pivot this arm will be caused by workmen leaning backward against the rail and in this instance the movement of the arm 26 would be positively blocked by the pin 29.

In Fig. 2, I have shown the horse completely knocked down and ready for storage or transport. Here the four legs L are laid one on top of the other. The arm 26 is pulled down against the cross bar 18 and the cross bar 18 is placed against the stacked legs 11 with the openings 31, 32 therein in registration with the openings 14, 15 of the

legs. Rail support bar 26 has an opening 26a registering with the opening 31 of cross piece 18 when the support bar is folded.

The eye bolts 22 receive the reduced ends 19 of the cross bar 10, the cross bar being held against coming out of the eyes by applying the nuts 20 and washers 21, to the projecting threaded ends thereof. The shanks of the eye bolts extend through the aligned openings 14, 31, and 26a, 15 and 32, respectively, and the nuts 23 are screwed on to the projecting ends of the shanks, whereby all of the parts are locked together with the round cross bar 10 spaced slightly above the stacked flat legs and cross bar 18. Thus the cross bar 10 serves as a convenient handle for transporting the knocked down structure.

In Figs. 5 and 6, I have illustrated a slight modification of the invention peculiarly adapted for use as a carpenter's horse. Here angular legs L', corresponding to the legs L, are arranged in pivoted pairs at each end of the horse and connected by a cross bar 10', corresponding to the cross bar 10, and similarly secured by nuts 20', corresponding to the nuts 20. In this instance the notches 16' in the upper ends of the legs L' serve to support a narrow cross piece or platform 40. In this case again, downward pressure on the platform will tend to cause it to be gripped more tightly by the cradle-forming notches.

In order to assure a highly rigid construction, means is provided for applying a strong downward pressure on the platform 40 at the time the latter is assembled on the legs L'. With this in view a counter-sunk opening 41 is provided at the center of the platform and in this recess is mounted a headed bushing 42, the shouldered portion 43 of which abuts the upwardly facing counter-sunk shoulder 44 of the opening 41. The closed top of the bushing has a fillister slot 45 therein for coaction with a screw driver and the cylindrical downwardly facing socket portion 46 of the bushing is internally threaded for coaction with the threaded shank of a downwardly extending eye bolt 47. The eye of this bolt is interlocked with the eye of a similar bolt 48, the shank of which extends through an opening 49 in the cross bar 10' and is engaged by a thumb nut 50.

When the thumb nut 50 is tightened, platform 40 is drawn downwardly against the shoulders of the notches 16' causing the platform and the legs to be held together firmly as a unit.

It will be evident from the foregoing description that in both forms of the invention the load applied to the horse instead of tending to collapse it, is merely operative to move it into more effective load-sustaining position; also that a device embodying the invention may be quickly erected, quickly knocked down or collapsed and occupies a minimum of space when disassembled and tied together for storage. All of the constituent elements of the horse may be cheaply manufactured of standard bar or rod stock, no complex or expensive parts being required, and due to the fact that all of the leg members are identical, the device is fool-proof against improper assembly.

Having thus described my invention and illustrated its use, what I claim as new and desire to secure by Letters Patent is:—

1. In a horse of the class described, spaced pairs of connected legs diverging at their upper and lower ends, a cross bar supported on the tops of the legs, a cross member connecting the intermediate portions of the legs at their pivotal points and affording pivotal connection therefor, each of said legs and said cross bar having equi-dis-

tantly spaced pairs of apertures therein adapted for registration when the horse is knocked down and the legs and the upper cross bar are laid one upon the other.

- 5 2. In a horse of the class described, spaced pairs of connected legs diverging at their upper and lower ends, a cross bar supported on the tops of the legs, a cross member connecting the intermediate portions of the legs at their pivotal points 10 and affording pivotal connection therefor, each of said legs and said cross bar having equi-distantly spaced pairs of apertures therein adapted for registration when the horse is knocked down and the legs and the upper cross bar are laid one upon the other, eye bolts adapted to be passed through certain of the aligned apertures in the legs when the horse is set up, whereby to prevent pivotal movement of the legs, the cross bar which affords the pivots for the legs including reduced 20 ends adapted to be passed through the eyes of the bolts when the horse is disassembled, and the eye bolts passed through the registering openings in the legs and in the upper cross bar when the horse is disassembled.
- 25 3. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, and a guard rail support bar pivotally connected to the upper cross piece and adapted to extend perpendicularly thereof when in operative position.
- 30 4. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, a guard rail support bar pivotally connected to the upper cross piece, and means to limit the pivotal movement 40 of the bar so as to arrest it in a perpendicular position with respect to the upper cross piece.

- 45 5. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, a guard rail support bar pivotally connected to the upper cross piece, and means to limit the pivotal movement 50 of the bar in one direction, comprising a pin projecting laterally from the upper cross piece and serving as an abutment for the pivoted end of

the bar when the bar is swung to upright position.

6. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, a guard rail support bar pivotally connected to the upper cross piece, means to limit the pivotal movement of the bar in one direction, comprising a pin projecting laterally from the upper cross piece and serving as an abutment for the pivoted end of the bar when the bar is swung to upright position, said bar having a recess therein in which said pin is accommodated when the bar is swung into inoperative position parallel to the cross piece.

- 80 7. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, a guard rail support bar pivotally connected to the upper cross piece, and means at the upper end of the bar for supporting a guard rail.

- 85 8. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, a guard rail support bar pivotally connected to the upper cross piece, and means at the upper end of the bar for supporting a guard rail, said guard rail support bar being adapted when in inoperative position to rest at the side of the cross piece and having an aperture registering with a corresponding aperture in the cross piece to accommodate means for securing the bar and cross piece together when the bar is in its inoperative position.

- 90 9. A device of the class described including spaced pairs of legs, means connecting the spaced pairs of legs and affording pivotal connections for the legs of each pair, the legs of each pair diverging above and below the pivots, a cross piece disposed between and supported by the divergent upper ends of the pairs of legs, a guard rail support bar pivotally connected to the upper cross piece, and a gauge pin projecting laterally from the upper end of one of the legs and to limit the pivotal movement of the guard rail support bar 100 in one direction.

HAROLD J. MARLOWE.
